CHARGE EJECTING NAIL POLISH
APPLICATOR

Delbert J. Bozzalla, Los Angeles, Calif.

Application March 6, 1950, Serial No. 147,970

2 Claims. (Cl. 15—137)

1

My present invention relates to applicators generally, and particularly to means for applying colored lacquers and other liquids to the nails of the fingers and toes as a part of the feminine toilet.

An object of my invention is to provide a device particularly adapted, although not necessarily, for the application of nail polish to the finger and toe nails, and structurally characterized by a minimum number of simply and inexpensively constructed parts capable of being quickly assembled to define a handle-forming reservoir for the nail polish, supporting a brush head into which a charge of nail polish may be positively delivered from the reservoir through a valve-controlled outlet thereof, by manipulation of an actuator with a finger of the hand in which the device is being held, all in such manner as to greatly facilitate application of the polish to the nails by dispensing with the usual bottle of nail polish and a separate brush which must be dipped into the small neck of the bottle several times with considerable care and skill during the polish-applying operation in order to avoid smearing the bottle or dipping the brush too deeply and transferring an excessive amount of polish to the brush.

Another object of my invention is to provide an applicator of the class described whose construction renders it absolutely leak-proof irrespective of variations in temperature, as well as to obviate clogging of the working parts from evaporation of the volatile vehicle such as amyl acetate which is generally used for compounding nail polish.

A further object of my invention is to provide an applicator whose parts may be molded of plastics and assembled to form a compact, streamlined structure which may be sold at a reasonable price and will function with maximum efficiency for an indefinite period of time.

Still another object of my invention is to provide an applicator of the above described character embodying a brush which, in the manufacture of the brush head, has its bristles compressed sufficiently to co-act with nail polish in restricting the passage of air to such extent that a temporary partial vacuum will be created in the charge-receiving passage of the liquid reservoir when the return or idle stroke of the plunger which works in such passage is effected, all in such manner that when the plunger clears one end of the passage upon completion of the return stroke, a charge of nail polish from the reservoir will be automatically sucked into the

passage for positive ejection therefrom into the brush bristles when the next forward or working stroke of the plunger is effected.

With these and other objects in view, my invention resides in the combinations, arrangements and functional relationships of elements as set forth in the following specification and particularly pointed out in the appended claims.

In the accompanying drawings,

10 Figure 1 is a longitudinal axial sectional view of one form of charge ejecting nail polish applicator embodying my present invention, and illustrating the applicator sealed for carrying about the person or in a handbag;

15 Figure 2 is a view similar to Figure 1 and showing the position of the working parts preparatory to delivering a charge of nail polish to the brush;

Figures 3, 4, 5 and 6 are enlarged transverse sectional views taken on the lines 3—3, 4—4, 5—5 and 6—6, respectively, of Figure 1; and

20 Figure 7 is a further enlarged fragmentary longitudinal sectional view of the brush taken on the line 7—7 of Figure 2.

25 Referring specifically to the drawings, my present invention comprises a cylindrical barrel 10 streamlined towards its rear end which is provided with internal screw threads 11 to receive the external screw threads 12 of a filler plug 13. The forward end of the barrel is also internally

30 screw threaded at 14 to receive the external screw threads 15 of the cylindrical body portion 16 of a head or brush holder 17 to define in the barrel a liquid reservoir 18 which is prolonged into a laterally offset longitudinal duct 19 in the head 17 having its forward end communicating with the rear end of a coaxially related passage 20 of relatively small diameter.

35 The forward streamlined end of the head 17 is provided with a cylindrical socket 21 co-axially related to the forward end of the passage 20 which communicates with the socket for the delivery of a charge of nail polish from the reservoir 18 to a brush B which is fitted in the socket as will be later described in detail.

40 Co-axially related to the duct 19 and extending freely therethrough is a plunger 25, the forward end of which is confined by guides 26 for reciprocating movement into and out of the passage 20. In its advanced position shown in Figure 1, the forward end of the plunger acts as a valve to seal the passage 20 against the leakage of liquid from the reservoir 18, and the tip end of the plunger enters the bore of an elastic sealing washer 27 seated in the bottom of the socket 21 as clearly shown in this figure. In the re-

tracted position of the plunger 25 shown in Figure 2, the plunger is guided by the guides 26, as the tip end of the plunger clears the inner end of the passage 20 so as to place the latter in communication with the duct 19 through the inlet passages 28 between the guides.

The opposite end of the plunger 25 is provided with an eye 30 through which freely projects the short leg 31 of an L-shaped connector 32, the long leg 33 of which is freely slidable in a longitudinal bore 34 in the head 17 which is in parallelism with the length of the passage 20. The free end of the leg 33 has a force fit in a socket 35 of an actuator or finger piece 36 which is of segmental shape in cross section as shown in Figure 5, and has a flat, longitudinally grooved face 37 which receives a flat, longitudinal tongue 38 on the head 17 to mount the actuator on the head for reciprocating movement.

The cylindrical portion 16 of the head 17 is provided with a segmental recess 40 slidably receiving the actuator 36. A coil spring 41 is mounted on the leg 33 of the connector 32 and extends freely into a deep pocket 42 in the head, with the ends of the spring bearing against the bottoms of the recess 40 and pocket 42 to urge the actuator 36 and hence the plunger 25 as a unit to the advanced position shown in Figure 1. Mounted on the long leg 33 is an elastic sealing washer 43 and a follower collar 44 which, under the action of the spring 41, seals the bore 34 against leakage of nail polish from the reservoir.

From Figure 7 it will be noted that the brush B is composed of an outer tube 50 which receives the brush bristles 51. A stop collar 52 is forced into one end of the tube 50 over the bristles 51 and forms an annular stop against which the bristles are pressed by a delivery tube 53 of relatively small diameter which is forced into the other end of the outer tube 50 co-axially thereof, for co-action with the stop collar in compressing the bristles between the latter and delivery tube at 54 for a purpose to be later described. The outer tube 50, which forms the head of the brush, is a tight friction fit in the socket 21, and seats against the sealing washer 27, with the bore of the delivery tube 53 in communication with the passage 20 to receive nail polish therefrom.

The actuator 36 has a serrated, cupped nose 55 to receive a finger tip for movement of the actuator to its retracted position shown in Figure 2. A streamlined cap 56 frictionally fits over the forward end of the barrel 10 so as to enclose the brush B and protect same as well as all working parts when the applicator is not in use.

In operation, let it be assumed that the reservoir 18 is supplied with a quantity of nail polish, so that upon removing the cap 56 the applicator may be grasped in the hand while a finger thereof moves the actuator 36 from its advanced position shown in Figure 1 to its retracted position of Figure 2, thus moving the plunger 25 so that its forward end clears the inner end of the passage 20 and is being guided by the guides 26.

With the brush B of the applicator lowermost, the nail polish from the reservoir will flow through the duct 19 and passages 28 into the passage 20, so that upon the release of the actuator, the spring 41 will force the charge of nail polish from the passage through the delivery tube 53 into the brush bristles. Once the brush has received a quantity of nail polish, the latter will co-act with the compressed area

54 of the bristles (Figures 2 and 7) to restrict the passage of air into the passage 20 to such extent that a temporary partial vacuum will be created in the passage when the plunger is retracted by the actuator as aforesaid. Thus when the plunger 25 clears the inner end of the passage, the effect of the vacuum in the latter will be to draw a charge of nail polish from the reservoir into the passage irrespective of the position in which the applicator is being held, whereby to insure that a charge of nail polish will enter the passage from the reservoir each time that the plunger is retracted by the actuator.

It will be clear that the pressure imposed upon the nail polish in the passage by the plunger when advanced therein by the spring 41 upon the release of the actuator 36, will be sufficient to overcome the resistance of the compressed bristle area 54 to the flow of the polish, so that the polish will be forced past such areas of the bristles to the forward end of the brush for application to the fingers or toes. Successive operations of the actuator 36 will deliver nail polish to the brush in measured charges so as to enable all the nails to be painted with the utmost ease and dispatch and without any waste or spilling of the polish.

I claim:

1. A charge ejecting applicator for viscous liquids comprising: a barrel providing a reservoir for the liquid; a head closing one end of the barrel and having a passage of relatively small diameter, with plunger guides at the inner end of the passage spaced to define passages providing communication between the reservoir and passage; a plunger working in said passage and guides to occupy a retracted position wherein the plunger clears the inner end of the passage to permit liquid from the reservoir to enter the passage through said passages, and an advanced position wherein the plunger enters and closes off the passage from the reservoir so as to eject the charge of liquid from the outer end of the passage; a manually operable actuator mounted on said head for reciprocating movement; means operatively connecting said plunger to said actuator for movement by the latter to retracted position; a spring urging the actuator and plunger as a unit to move the plunger to its advanced position; said head having a socket of relatively large, uniform diameter co-axially related to the outer end of said passage; a tube of uniform diameter frictionally fitting in said socket; bristles in said tube and projecting from the outer end thereof in brush formation; a stop collar of uniform diameter fitted in the outer end portion only of said tube around said bristles; and a delivery tube communicating with the outer end of said passage and being forced into said bristles from the inner end of the first said tube to co-act with said stop collar in constricting the bristles between the inner end of the stop collar and the forward end of the delivery tube so as to set up a permanent restriction to the flow of air through the brush in order to enable a partial vacuum to be temporarily created in the passage when the plunger is moved to said retracted position, for the automatic filling of the passage with liquid from the reservoir under the action of said vacuum.

2. A charge ejecting applicator for viscous liquids comprising: a barrel providing a reservoir for the liquid; a head closing one end of the barrel and having a longitudinally extending duct

laterally offset from the longitudinal axis of the head; said head having a passage of relatively small uniform diameter at the outer end of said duct, with plunger guides in said duct at the inner end of said passage spaced to provide circumferentially spaced longitudinally extending passages for liquid from the reservoir to the passage; a plunger reciprocably mounted in said passage and said guides to occupy a retracted position wherein the plunger is supported in the guides for the flow of liquid from the reservoir through said passages to the passage, and an advanced position wherein the plunger enters and closes off the passage from the reservoir so as to eject the liquid from the outer end of the passage; a manually operable actuator mounted on said head for reciprocating movement; an L-shaped connector having a short leg operatively connected to said plunger, and a long leg slidably mounted in said head and fixed to said actuator so as to effect movement of the plunger to advanced or retracted position according as the actuator is moved to one extreme position or the other; a coil spring mounted on said long leg and co-acting with the head and actuator to urge the latter and plunger as a unit to move the plunger to its advanced position; said head having a socket of relatively large uniform diameter co-axially related to the outer end of said passage; a tube of uniform diameter frictionally fitting in said socket; bristles in said tube and projecting from the outer end thereof in brush formation; a stop collar of uniform diameter fitted in the outer end portion only of
